CLAIM

The ornamental design for a tire gauge as shown and described.

DESCRIPTION

FIG. 1 is a perspective view of a tire gauge according to an embodiment of the invention;

FIG. 2 is a left side view of the tire gauge of FIG. 1;

FIG. 3 is a right side view of the tire gauge of FIG. 1;

FIG. 4 is a rear view of the tire gauge of FIG. 1;

FIG. 5 is a front view of the tire gauge of FIG. 1;

FIG. 6 is a top view of the tire gauge of FIG. 1; and,

FIG. 7 is a bottom view of the tire gauge of FIG. 1.

In the drawings, the matter shown in broken lines form no part of the claimed design.
